UNITED STATES PATENT OFFICE.

JOHN N. CLARKE, OF CINCINNATI, OHIO, ASSIGNOR OF TWO-THIRDS TO
SAMUEL T. J. COLEMAN AND EDMUND B. REYNOLDS, BOTH OF
SAME PLACE.

HORSESHOE-BLANK ROLL.

SPECIFICATION forming part of Letters Patent No. 275,022, dated April 3, 1883.

Application filed November 6, 1882. (No model.)

To all whom it may concern:

Be it known that I, JOHN N. CLARKE, a citizen of the United States, residing at Cincinnati, in the county of Hamilton and State of Ohio, have invented certain new and useful Improvements in Horseshoe-Blank Rolls, of which the following is a specification, reference being had therein to the accompanying drawings.

This invention comprises a special construction of roll, wherein the peculiar form of horseshoe-blank bar seen in Letters Patent No. 260,454, granted to me July 4, 1882, can be manufactured in the most rapid, economical, and uniform manner, the arrangement of the dies in said roll being hereinafter more fully described, and pointed out in the claim.

In the annexed drawings, Figure 1 is a front elevation of a pair of rolls employed for imparting the preliminary shape to the blank or bar. Fig. 2 is an enlarged transverse section of a bar after being run through the first "pass" of said rolls. Fig. 3 is a similar section of the bar after having traversed the second pass. Fig. 4 is an enlarged vertical section of the finishing-roll, a bar being shown in the act of passing through the same. Fig. 5 is a similar section of a modification of said finishing-roll. Fig. 6 is a modification of one of the passes in the forming-rolls. Fig. 7 is a transverse section of a bar produced by such a modification of the forming-rolls.

Referring to Fig. 1, A A' represent housings or standards that afford journal-bearings for a pair of forming-rolls, B C, said rolls having "passes" D E, capable respectively of imparting to the blank or bar substantially the different shapes seen in Figs. 2 and 3. These shapes, however, are only approximate, and may be varied considerably, according to the size and weight of shoe and the material of which it is composed, the object of said passes D E being to gradually reduce the rough blank or bar to a convenient form previous to being run through the finishing-roll F. (Seen in Fig. 4.) Reference to this illustration will show that two diametrically-opposite dies, G G', extend some distance around the periphery of said roll, which dies produce

the comparatively long marginal projections 50 seen in my patent herein referred to. Located at equal distances from the long die G, but on opposite sides of the roll, are two relatively shorter dies, H I, supplemented by a similar pair, H' I', which dies H H' I I' produce the 55 smaller marginal projections seen in said patent, it being understood that this roll F is arranged to form two precisely similar blanks at every revolution. Said roll may, however, be arranged to turn out three or more blanks 60 at every revolution, if desired. After the rough bar has been properly heated it is first run through the pass D, and is thereby reduced to the shape seen in Fig. 2. Said bar is then inverted and caused to traverse the 65 second pass, E, from which it emerges in the shape shown in Fig. 3. This reduced bar is now run through the finishing-roll F, as indicated by the arrow in Fig. 4, and, assuming that the dies I' I are the first to operate on 70 said bar, it is evident they form thereon a pair of short calks, K' K, which correspond with the projections C C'. (Seen in my patent previously alluded to.) Furthermore, it is apparent that the extended die G will form on 75 said bar a calk, L, corresponding to the long projection B, (seen in said patent,) while the continued revolution of said roll will cause the other dies, H H' and G', to act successively on the bar in the manner just described; hence 80 it is evident that every complete revolution of roll F produces two precisely similar blanks, each of which consists of a long projection and a pair of shorter calks, which blank can then be cut transversely, so as to afford the 85 two different forms of shoes seen in my patent referred to. The finishing-roll F may be modified in its construction, as seen in Fig. 5, where a somewhat shorter die, G'', is used instead of the die G'. Again, the dies H'' I'' 90 are not only shorter than the corresponding dies, H' I', (seen in Fig. 4,) but are located comparatively near the die G'', while the dies H I are somewhat remote from the die G. Consequently that portion of the roll including the set of dies I G H will produce a longer blank than will the same dies seen in Fig. 4; but the other set of dies, H'' G'' I'', will turn 95

out a shorter blank than the dies H' G' I'. It therefore follows that every complete revolution of the roll F (seen in Fig. 5) will produce one long blank and another shorter one.

5 The rolls above described are used for manufacturing blanks having truncated ridges or projections; but when it is desired to furnish sharp ridges, so as to afford a bar capable of being made up into winter shoes, the rolls B C 10 should have a pass approximating what is shown at M in Fig. 6. This pass will produce a blank having the transverse section seen at J' in Fig. 7.

15 I claim as my invention—
The roll F for finishing horseshoe blanks or

bars after they have been reduced to the proper form by a set of shaping-rolls, substantially as described, said roll F being provided with a pair of long dies, G G', between which and on opposite sides of the roll are situated two 20 pairs of shorter dies, H H' I I', whereby is produced the peculiar blank seen in my patent herein referred to.

In testimony whereof I affix my signature in presence of two witnesses.

JOHN N. CLARKE.
